United States Patent Office

Des. 229,574

Patented Dec. 11, 1973

229,574

TOY RECORD PLAYER

Paul A. Martin, East Aurora, N.Y., assignor to The Quaker Oats Company, Chicago, Ill.

Filed Dec. 30, 1971, Ser. No. 214,532

Term of patent 14 years

Int. Cl. D21—01

U.S. Cl. D34—15 C

FIG. 1

FIG. 2

FIG. 3

FIG. 4

FIG. 1 is a top plan view of a toy record player showing my new design;

FIG. 2 is a front elevation thereof;

FIG. 3 is a side elevation thereof, as seen from the left in FIG. 1; and

FIG. 4 is a rear elevation thereof.

I claim:

The ornamental design for a toy record player, substantially as shown.
